(57) **CLAIM**

The ornamental design for a device for attachment to a fishing rod for securing a fishing line with attached sinker, as shown and described.

DESCRIPTION

FIG. 1 is a front and top perspective view of a device for attachment to a fishing rod for securing a fishing line with attached sinker, showing my new design;

FIG. 2 is a front view thereof, the unshown opposite rear view being of identical appearance;

FIG. 3 is a top view thereof;

FIG. 4 is a bottom view thereof;

FIG. 5 is a side view taken from the right of FIG. 2;

FIG. 6 is a side view taken from the left of FIG. 2; and,

FIG. 7 is a rear and top perspective view thereof shown in functional relationship with a fishing rod and associated fishing line with attached sinker illustrated in phantom outline, neither being a part of this invention.
